[57] CLAIM

The ornamental design for a portable pitching mound, as shown and described.

DESCRIPTION

FIG. 1 is a perspective view of a portable pitching mound showing my new design;

FIG. 2 is a reduced top plan view;

FIG. 3 is a right side elevation view thereof;

FIG. 4 is a rear elevation view thereof; and,

FIG. 5 is a front elevation view thereof.

The bottom is unornamented.

It is understood that the texture on the trapezoidal top surface is continuous.
